DESIGN FOR A COMBINED TRAVELING CASE AND COSMETIC HOLDER

Arthur R. Botham, New York, N. Y., assignor to Coty, Inc., Wilmington, Del., a corporation of Delaware

Application January 28, 1942, Serial No. 105,469

Term of patent 7 years

To all whom it may concern:

Be it known that I, Arthur R. Botham, a citizen of the United States, residing in the city and State of New York, have invented a new, original, and ornamental Design for a Combined Traveling Case and Cosmetic Holder, of which the following is a specification, reference being had to the accompanying drawings, forming a part thereof.

In the drawings

Figure 1 is a perspective view of a combined traveling case and cosmetic holder showing my new design, the traveling case being in the open position.

I claim:

The ornamental design for a combined traveling case and cosmetic holder, as shown.

ARTHUR R. BOTHAM.
